UNITED STATES PATENT OFFICE

HAROLD G. RICE, OF CHICAGO, ILLINOIS

BOTTLE CAPPER

Application filed January 14, 1929. Serial No. 332,299.

This invention relates to bottle cappers and more particularly to that type comprising an upright frame or standard having a base for supporting and anchoring the device on and to a bench or other support to receive the bottles to be capped thereon, the upper end portion of the frame or standard overhanging the base—that is, being curved or extended forwardly and having a vertical guideway receiving for vertical reciprocation therein, the shank of a plunger formed with a rack bar and carrying a capping head at its lower end and also having an axially horizontal pinion engaging the teeth of the rack bar, and a handle for rotating the pinion.

A principal object of the invention is to provide novel means for releasing the pinion from operative engagement with the rack bar to permit the plunger and capping head to slide free thereof, so that the plunger and the handle may both be readily adjusted to proper capping position according to the height of the bottle to be capped.

With the above and other objects in view, the invention consists in certain novel structure and arrangement of parts to be herein-after more particularly specified and pointed out in the claims.

In the accompanying drawings:—
30 Fig. 1 is a perspective view of my novel bottle capper.

Fig. 2 is an enlarged fragmentary front elevation of the upper portion of the capper.

35 Fig. 3 is a sectional view taken on the line 3—3 of Figure 4.

Fig. 4 is a sectional view horizontally on the line 4—4 of Figure 3, and

40 Fig. 5 is an elevation of the operating shaft with a pinion formed thereon.

Referring to the drawings in detail, the capper is shown as comprising a base 6 having as part of its frame an upright standard 7, the upper portion of which is curved or 45 extended forwardly as at 8 to overhang the base 6. While the base and upright are shown formed of cast metal, it is to be understood that the same may be constructed in any suitable manner—of sheet metal or otherwise. The base has suitable apertures 9 at

the forward corners and apertures 10 on each side of the upright or standard 7 to anchor the device to a bench or other support and the bottles 11 are adapted to be supported upon a ribbed cushion 12 of rubber or the like suitably anchored to the base.

The upright or standard 7 is substantially T-shaped in cross section but may be of other suitable section and preferably tapers to its upper end where it is formed with a sleeve-like boss or enlargement 13 in one end of which there is bored an axially horizontal cylinder opening 14 terminated by the opposite end wall 15 which is bored out to form a bearing or opening of reduced size co-axial 65 with the bore 14.

A vertical guideway 16 is arranged with its opening communicating with the bore 14 and in such a manner that its axis is directly over the center point of the cushion 12 on the base 6, although this is not absolutely essential. The sleeve or guideway 16 receives for vertical reciprocation therein the shank portion of a plunger 17 formed with a rack bar 18 along its inner edge but terminating short 75 of the upper end of the plunger as well as short of the lower end thereof as indicated at 19 and 20 to provide shoulders or stops to limit the reciprocation of the plunger as will be more fully described. The lower end of 80 the plunger carries a capping head 21 having a cushion washer 22 mounted therein as usual. This capping head is secured against the shoulder formed at the bottom of the plunger by means of a reduced portion 23 which extends through an axial opening in the top or end wall of the capping head and is then riveted or upset as indicated at 24 to secure the capping head in position.

A shaft 25 fits the bore of the horizontal 90 sleeve 13 and has a reduced end portion 26 which fits and extends through the opening of the end wall 15 while the shaft proper extends through the enlarged opening 14, thus permitting the shaft to be inserted in position in assembling the parts. The shaft 25 is milled as indicated at 27 to provide a pinion intermediately adapted to mesh with the teeth of the rack bar 18 and in order to hold the parts in this position, a compression coil 100

spring 28 is mounted on the reduced extension 26 of the shaft 25 and between the end wall 15 and nut 29 on the end of the shaft so as to normally force the shaft to the full line positions shown in the drawings and more particularly in Figures 2 and 4. In this position of the shaft 25, the end wall 15, against which the annular shoulder formed by the ends of the pinion teeth engages, constitutes means for limiting the sliding movement of the shaft and its pinion under the influence of the spring, thereby to normally maintain the pinion in mesh with the rack bar. However, the pinion may be disengaged from the teeth of the rack bar by shifting the shaft either by pressure on the nut 29 or otherwise, as indicated in dotted lines in Figures 2 and 4 so that the plunger and capping head may be quickly and easily adjusted so that the capping head will be accommodated to bottles of different heights, as disclosed in Figure 1.

A handle 30 is mounted on the shaft 25 for rotating the latter to reciprocate the plunger and capping head during the capping operation. Obviously, by rotating the shaft in one direction the capping head will be raised and by rotating the shaft in the opposite direction, the capping head will be lowered for applying a cap. Considerable pressure may be brought to bear in the capping operation due to the leverage produced by this construction.

It will also be apparent that when the plunger and capping head are elevated the movement will be limited by engagement of the shoulder 20 with the teeth of the pinion 27, and in the opposite direction, the lowering of the rack bar and capping head will be limited by engagement of the shoulder 19 with the teeth of the pinion 27, thus preventing displacement of the plunger from its sleeve 16. In addition, although the shaft 25 is shifted so that the teeth of the pinion 27 are displaced laterally out of the path of the teeth of the rack bar 18, yet the shoulders 19 and 20 will prevent displacement of the plunger by engagement with the reduced portion 26. The plunger cannot be removed from its sleeve unless the shaft 25 is entirely removed from its bearing sleeve 13 after removal of the enlargement or nut 29.

It should be noted from Figure 4 that, while the portion 26 of the shaft 25 is sufficiently reduced in diameter to permit free sliding movement of the plunger 17 along its longitudinal axis when the shaft is shifted to the dotted position shown in Figure 4, this portion is not small enough in diameter to permit rotation of the plunger 17 about its axis, but serves as an effective stop to prevent such rotation.

While I have shown and described my invention in a preferred form, I am aware that

various changes and modifications may be made therein without departing from the principles of the invention, the scope of which may be determined by reference to the appended claims.

I claim as my invention:

1. A bottle capper comprising a base having an upright with an overhanging upper portion, having a horizontal sleeve with a reduced bore at one end and a vertical sleeve communicating therewith, a plunger in the vertical sleeve having a rack bar with shoulders at the ends thereof and a capping head at its lower end, a shaft in the horizontal sleeve having a reduced end engaging the reduced bore and having a pinion intermediate adjacent the reduced portion, a spring on the reduced portion engaging the end wall of the horizontal sleeve at its reduced bore, an enlargement on the reduced end of the shaft whereby the spring holds the shaft in position with the pinion engaging the rack bar but adapted to permit said shaft to be displaced to disengage the pinion from the rack bar whereby the plunger may be adjusted vertically independent of the shaft, and a handle on the shaft for actuating the same.

2. In a device of the class described and in combination, a frame having a horizontal sleeve and a vertical sleeve with communicating bores, a shaft rotatable in said horizontal sleeve and having operating means thereon, said shaft having pinion teeth and being reduced in diameter adjacent said teeth, a plunger reciprocable in said vertical sleeve and having rack teeth thereon engageable with said pinion, means normally retaining said pinion in engagement with said rack and permitting disengagement thereof while retaining said shaft in its sleeve, and means on said plunger abutting against the reduced portion of said shaft when the pinion is operatively disengaged from said plunger for preventing withdrawal of said plunger from its sleeve.

3. In a device of the class described and in combination, a frame comprising a base portion and a vertical overhanging guide portion and having a transverse opening constituting a bearing adjacent said guide portion, a capping plunger slidably mounted in said guide portion and having rack teeth formed thereon, a shaft rotatably mounted in said bearing and having a pinion formed thereon adapted to co-operate with said rack for reciprocating the same, said shaft being reduced in diameter adjacent said pinion and having an endwise displacement within said bearing sufficient to disengage the pinion from the rack teeth of the plunger, means for rotating the shaft, and means normally maintaining said pinion in operative engagement with said rack and also permitting said shaft to be axially displaced a distance equal

to the width of said pinion to bring the reduced portion of the shaft across the plunger, whereby the pinion may be disengaged from the rack teeth and the plunger freed for 5 quick endwise adjustment.

4. In a device of the class described and in combination, a frame comprising a base portion and vertical overhanging guide portion and having a transverse opening constituting a bearing adjacent said guide portion, a capping plunger slidably mounted in said guide portion and having rack teeth formed thereon, a shaft rotatably mounted in said bearing and having a pinion formed thereon adapted 10 to co-operate with said rack for reciprocating the same, said shaft being reduced in diameter adjacent said pinion and having an endwise displacement within said bearing sufficient to disengage the pinion from the rack teeth of 15 the plunger, means for rotating said shaft, and means normally maintaining said shaft at one endwise limit with said pinion in operative engagement with said plunger, said last-named means also permitting said shaft 20 to be axially displaced to bring the reduced portion of the shaft across the plunger thereby withdrawing said pinion from engagement with said rack and thus freeing the plunger for quick longitudinal adjustment.

5. In a device of the class described and in combination, a frame comprising a base portion and a vertical overhanging guide portion having a transverse opening therein constituting a bearing, a capping plunger slidably mounted in said guide portion and having rack teeth formed thereon, a shaft rotatably mounted in said bearing and having a pinion formed thereon adapted to cooperate with said rack for reciprocating the same, 35 said shaft being reduced in diameter adjacent said pinion and having an endwise displacement within said bearing sufficient to disengage the pinion from the rack teeth of the plunger, means for rotating said shaft, and 40 resilient means normally maintaining the shaft at one endwise limit with said pinion in operative engagement with said rack and permitting axial displacement of said shaft for withdrawing said pinion from engagement with said rack and for moving the reduced portion of the shaft across the plunger, whereby said plunger may be quickly adjusted longitudinally.

6. In a device of the class described and in combination, a frame comprising a base portion and a vertical overhanging guide portion having a transverse opening therein constituting a bearing, a capping plunger slidably mounted in said guide portion and having rack teeth formed thereon, a shaft rotatably mounted in said bearing and having a pinion formed thereon adapted to co-operate with said rack for reciprocating the same, 55 said shaft being reduced in diameter adjacent said pinion and having an endwise dis-

placement within said bearing sufficient to disengage the pinion from the rack teeth of the plunger, means for rotating said shaft, an enlarged member on the reduced portion of said shaft, and a helical spring disposed on 70 said reduced portion between said enlarged member and said pinion for normally maintaining said shaft at one endwise limit with said pinion in operative engagement with said rack, said shaft being axially displaceable 75 against the resilient action of said spring for a distance equal to the width of said pinion, whereby the plunger will be freed for quick longitudinal adjustment.

7. In a bottle capper, the combination of a 80 base provided with a standard rising therefrom, a rack bar slideable vertically in said standard and provided at its lower end with a capping head over said base, an axially horizontal pinion rotatably supported in the upper portion of said standard and having its teeth normally engaging the teeth of the rack bar, said pinion being also slidably supported in said standard and shiftable axially on its support and out of mesh with the rack 90 bar, a spring for forcing the pinion into mesh with the rack bar, means for limiting the sliding movement of the pinion so that the spring will normally maintain it in mesh with the rack bar, and a handle connected to said 95 pinion for rotating the latter.

8. In a bottle capper, the combination of a base provided with a standard rising therefrom, an axially horizontal pinion rotatably supported in the upper portion of 100 said standard, a rack bar slideable vertically in said standard and provided at its lower end with a capping head over said base, an extension on one side of and integral with said pinion constituting a trunnion for the 105 pinion rotatable in the standard and slidably supporting the pinion in the standard so that the pinion may be shifted axially in its support on the standard a distance substantially equal to the width of the operative face of 110 the pinion, a spring for normally urging the pinion axially into mesh with the rack bar, means for limiting the sliding movement of the pinion, and a handle connected to said 115 pinion for rotating the latter.

9. In a device of the class described and in combination, a frame comprising a base portion and a vertical overhanging guide portion and having a pair of spaced axially horizontal bearing apertures of different diameters adjacent said guide portion, a capping member vertically slideable in said guide portion and having rack teeth formed thereon, a shaft having trunnions of different diameters rotatably journaled in and extending outside of said bearings and having a pinion thereon of external diameter not greater than the diameter of the larger of 120 said apertures and having an endwise displacement within said bearing sufficient to 125 130

- disengage the pinion from the rack teeth of the plunger, and a compression spring surrounding said smaller trunnion extension and serving to maintain said pinion in operative engagement with the rack while permitting a sufficient sliding movement of the pinion to unmesh same from the rack so as to permit free sliding movement of the capping member.
10. 10. In a device of the class described and in combination, a frame comprising a base portion and vertical overhanging guide portion and having a transverse opening constituting a bearing adjacent said guide portion, a capping plunger slidably mounted in said guide portion and having rack teeth formed thereon, a shaft rotatably mounted in said bearing and having a pinion formed thereon adapted to co-operate with said rack for reciprocating the same, said shaft being reduced in diameter adjacent said pinion and having an endwise displacement within said bearing sufficient to disengage the pinion from the rack teeth of the plunger and in substantially any angular position of the pinion, means for rotating said shaft, and means normally maintaining said shaft at one endwise limit with said pinion in operative engagement with said plunger, said last-named means also permitting said shaft to be axially displaced to bring the reduced portion of the shaft across the plunger thereby withdrawing said pinion from engagement with said rack and thus freeing the plunger for quick longitudinal adjustment.

HAROLD G. RICE.
